UNITED STATES PATENT OFFICE.

GEORGE M. MURRAY, OF WEST DULUTH, MINNESOTA.

STOVE-LID AND DRAFT MEANS.

1,281,635.

Specification of Letters Patent. Patented Oct. 15, 1918.

Application filed August 7, 1917. Serial No. 184,910.

To all whom it may concern:

Be it known that I, GEORGE M. MURRAY, a citizen of the United States, residing at West Duluth, in the county of St. Louis and 5 State of Minnesota, have invented a new and useful Stove-Lid and Draft Means; and I do hereby declare the following to be a full, clear, and exact description of the invention, such as will enable others skilled in the 10 art to which it appertains to make and use the same.

This invention relates to an improved stove lid and draft means carried thereby, and an object of the invention is to provide 15 a device of this kind, in which the stove lid is provided with a downwardly projecting draft tube, designed to extend substantially to the grate bars and below the fire bed, whereby a draft may be created through 20 said tube and the fire bed and the outlet flue, instead of through the ash pit.

A further object of the invention is to provide a stove lid having a guide for the reception of a slide whereby the tube may 25 be covered or closed, for cutting off the said draft.

In practical fields the details of construction may necessitate alterations falling within the scope of what is claimed.

30 The invention comprises further features and combination of parts as hereinafter set forth shown in the drawings and claimed.

In the drawings:-

Figure 1 is a plan view of a conventional 35 form of cooking stove, showing the improved stove lid applied thereto.

Fig. 2 is a sectional view on line 2-2 of Fig. 1.

Fig. 3 is an enlarged detail sectional view 40 on line 3-3 of Fig. 1.

Fig. 4 is a sectional view through a stove lid, showing the draft tube provided with an adjustable section.

Referring more especially to the drawings 45 1 designates the top plate of a conventional form of cooking stove, and which is provided with the usual stove openings 2 and 3, which are closed by the lids 4 and 5. Each of the lids 4 is provided with an elongated depression 6 acting as a guide. Depending downwardly from each lid 4 and at one end of its depression is a draft tube 7, which has its lower end in close position to the grate bars 8 of the fire box 9. In fact the down 55 draft tube 7 is eccentric to the center of the lid, whereby the lid may be rotated to dif-

ferent positions, so that the down draft tube may be positioned at different locations in the fire bed. For instance if the fire is somewhat dead at the end of the fire box or in 60 the center, or to the sides, the down draft tube may be positioned accordingly, by turning the lid. It is to be observed that there are two lids illustrated, and it is obvious that either one of the lids may be rotated to position the tubes 7 accordingly if either or both ends of the fire is dead. It is further obvious that if the center and one end or the other of the fire is dead, the down draft tubes may be positioned accordingly, 70 by rotating and positioning the respective lid accordingly. There is sufficient room or clearance allowance between the grate bars and the lower extremity of the draft tube, to permit the grate bars to be rattled, when 75 shaking the fire bed. The upper end of the tube 7 opens through the lid 4 at one end of said depression. A suitable slide 10, which is elongated, is mounted and guided in said depression 6, and designed to cover said 80 draft tube. This slide has a finger member 11 whereby the slide may be operated. By opening the slide 10 a draft may be created downwardly through the tube 7 and through the fire bed as indicated by the arrows 12, and up through the outlet flue 13, instead of creating the draft through the ash pit. The draft tube 7 is purposely provided to insure a direct and vertical draft 85 through the top lid of the stove directly over 90 the fire pot to a point close to the bottom of the fire bed, so that the draft will act instantaneously and directly upon the fire, and this construction, together with the means for controlling the draft, may be added to 95 all coal ranges now in use. This may be accomplished by simply supplying new lids to the stove lid openings above the fire box of all styles of coal ranges, either old or new. Furthermore, the lids may be cast and with 100 the tubes. The depressions in the lids for the reception of the controlling dampers may be formed at the time of casting. Telescoping into the tube 7 is a tube section 7^a which is provided with a plurality 105 of diametrically opposed apertures 7^b. Extending transversely of the tube 7 is a head pin or bolt 7^c, which may be arranged in certain of said diametrically opposed apertures 7^b, in order to hold the tube section 7^a 110 in different adjusted positions in the tube 7, whereby a draft tube may be provided

that can be used in connection with different depths of fire or grate bars. Furthermore the tube section 7^a may be adjusted to regulate the draft with relation to the bed of the fire.

6 The invention having been set forth what is claimed as new and useful is:—

1. The combination with a cook stove having its top plate provided with a stove lid opening, of a fire box directly below said opening, a stove lid engaging said opening, said lid having an eccentrically arranged opening, a cylindrical tube depending vertically from the marginal edge of the opening in the lid, and terminating adjacent the bottom of the fire box, said tube having its outlet end opening downwardly directly and axially with and below the opening in the lid and adjacent the bottom of the fire box, whereby a downward draft may be carried to the bottom of the fire bed, so that the draft may pass upwardly through either side of the fire bed, said lid having guides, and means adjustable in the guides for controlling the draft downwardly through the upper end of the tube, said tube comprising a stationary section and a telescopic section, the former telescopically receiving the latter, a pin detachably engaging the former section, the latter section having a plurality of diametrically oppositely disposed aper-

tures, any opposite two of which are adapted to receive said pin for holding the latter section in different vertical adjusted positions.

35

2. The combination with a cook stove having its top plate provided with a stove lid opening, of a fire box directly below said opening, a stove lid engaging said opening, said lid having an eccentrically arranged opening, a cylindrical tube depending vertically from the marginal edge of the opening in the lid, and terminating adjacent the bottom of the fire box, said tube having its outlet end opening downwardly directly and axially with and below the opening in the lid and adjacent the bottom of the fire box, whereby a downward draft may be carried to the bottom of the fire bed, so that the draft may pass upwardly through either side of the fire bed, said lid having guides, and means adjustable in the guides for controlling the draft downwardly through the upper end of the tube.

40

45 In testimony whereof I have signed my name to this specification in the presence of two subscribing witnesses.
